(57) **CLAIM**

I claim the ornamental design for a lighting fixture, as shown and described.

DESCRIPTION

FIG. 1 is a perspective view of a first embodiment of a lighting fixture, showing my new design;

FIG. 2 is a second perspective view of the lighting fixture of FIG. 1;

FIG. 3 is a front elevation view of the lighting fixture of FIG. 1, the back elevation view being a mirror image thereof;

FIG. 4 is a left elevation view of the lighting fixture of FIG. 1, the right elevation view being a mirror image thereof;

FIG. 5 is a perspective view of a second embodiment of the lighting fixture, showing my new design;

FIG. 6 is a second perspective view of the lighting fixture of FIG. 5;

FIG. 7 is a front elevation view of the lighting fixture of FIG. 5, the back elevation view being a mirror image thereof; and,

FIG. 8 is a left elevation view of the lighting fixture of FIG. 5, the right elevation view being a mirror image thereof.

The curved broken lines define the bounds of the claimed design and form no part thereof.
